Primary Examiner — Katie Jane Stofko*(74) Attorney, Agent, or Firm* — Andrus Intellectual Property Law, LLP(57) **CLAIM**

The ornamental design for an earbud tip as shown and described.

DESCRIPTION

FIG. 1 is a perspective view of an earbud tip showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a perspective view thereof, shown in an alternate position;

FIG. 9 is a front elevation view thereof;

FIG. 10 is a rear elevation view thereof;

FIG. 11 is a right side elevation view thereof; and,

FIG. 12 is a left side elevation view thereof.

The broken lines shown in FIG. 3 illustrate portions of the earbud tip that form no part of the claimed design.
